UNITED STATES PATENT OFFICE.

LIONEL BULL, OF CHICAGO, ILLINOIS.

TEAT-CUP.

1,144,346.

Specification of Letters Patent. Patented June 29, 1915.

Application filed April 24, 1914. Serial No. 834,077.

To all whom it may concern:

Be it known that I, LIONEL BULL, a subject of the King of England, residing at Chicago, in the county of Cook and State 5 of Illinois, have invented new and useful Improvements in Teat-Cups, of which the following is a full, clear, and exact description.

My invention relates to teat-cups for 10 milking machines, and particularly to the construction of the elastic tube of the same within which the teat of the cow is inserted.

The object of my invention is to provide 15 a tube that will be simple and economical in construction, and be easy to keep in a perfectly clean and sanitary condition, substantially as hereinafter fully described, and as particularly pointed out in the claims.

In the drawings, Figure 1 is a side view 20 of my improved teat-cup. Fig. 2 is a vertical central section thereof. Fig. 3 is a transverse section taken on dotted line 3-3, Fig. 2.

In the drawings, A represents the tubular 25 metal casing of the teat-cup. This casing tapers slightly from its upper wider end to its lower narrower end, and its upper end a is exteriorly threaded and made thicker to narrow the entrance to the bore thereof and 30 to widen the upper edge of the same, so as to provide a broad bearing surface for the outwardly flaring circumferential flange projecting from the upper end b of a cylindrical rubber tube B. This tube B is open 35 at both ends and is of a diameter less than the upper end or mouth of the bore of casing A, and is of such length that its lower end extends down through and out of the lower or discharge end of the casing, and 40 said tube is secured in a position concentric to the axis of the casing by means of an annular cap C which is screwed down over the upper end thereof and has an inwardly projecting flange c that provides an inner shoul- 45 der that engages the flange b of the tube and clamps the same against the broader edge of the upper end of the casing sufficiently tight to make the joint air and water tight.

50 The bore of the lower end of casing A is restricted by making the annular walls thereof thicker. At one side of this lower annular edge it is provided with a stub D which has a nipple d inserted longitudinally

into a suitable opening in the end thereof, 55 which nipple communicates with the annular chamber around tube B and connects the same to the adjacent end of a flexible pipe of a pulsator (not shown).

I insert in the lower end of the elastic 60 tube B the widened upper end e of another nipple E, and the diameter of this wider upper portion e is such as to make it necessary to distend the lower end of tube B to such an extent as to engage the inner circumference of the lower end of the bore of the casing A, and seal the same so as to make an air tight joint for the annular chamber between the tube B and the casing A, substantially as shown in the drawings. 70

The mouth or upper end of the tube B is, preferably, provided with a funnel-shaped apron F, which extends from the inner angle of the mouth of the tube at the point where the upper surface of the flange meets 75 the same down into the bore of the tube a short distance, substantially as shown in the drawings.

In operation, the teat of the cow is inserted down through the central opening of 80 the cap C into the bore of the elastic tube B which will stretch sufficient to accommodate the same. The pulsator of the milking machine is then put in operation and the annular chamber between casing A and the 85 outer circumference of said tube is alternately exhausted and charged by the introduction of more air therein; in other words, an alternate condition of vacuum and pressure is created in this annular chamber 90 which causes the tube B to be compressed so as to compress the teat of the cow and then to expand to its normal circumference so as to suck the milk from the cow, substantially in the same manner as now manipulated by hand. 95

What I claim as new is:

1. A teat-cup for a milking machine comprising an elastic cylindrical tube made open at its ends and having a funnel-shaped 100 apron extending into the mouth of the same, a hollow metal casing through which said tube extends, and means engaging the ends of said tube that attach the ends of said tube to the ends of said casing. 105

2. A teat-cup for a milking machine comprising an elastic cylindrical tube made open at its ends and having a funnel-shaped

apron extending into the mouth of the same and having a circumferential end flange projecting therefrom, a hollow metal casing through which said tube extends, and means 5 engaging the ends of said tube that attach the ends of said tube to the ends of said casing.

In witness whereof I have hereunto set my hand this 15th day of April, 1914.

LIONEL BULL.
